UNITED STATES PATENT OFFICE.

WILLIAM POLK, OF EAST LIVERPOOL, OHIO.

APPARATUS FOR FORMING SAGGARS.

SPECIFICATION forming part of Letters Patent No. 789,563, dated May 9, 1905.

Application filed June 9, 1904. Serial No. 211,817.

To all whom it may concern:

Be it known that I, WILLIAM POLK, a resident of East Liverpool, in the county of Columbiana and State of Ohio, have invented a new and useful Improvement in Apparatus for Forming Saggars; and I do hereby declare the following to be a full, clear, and exact description thereof.

My invention relates to apparatus for forming saggars and other hollow bowls, and more especially to certain improvements on an apparatus for which I filed an application for Letters Patent of the United States on the 24th day of July, 1903, Serial No. 166,884.

To enable others skilled in the art to make and use my invention, I will describe the same with reference to the accompanying drawings, in which—

Figure 1 is a front elevation. Fig. 2 is a side view on a reduced scale. Fig. 3 is a sectional view taken on the line 3 3, Fig. 2, looking in the direction of the arrow. Fig. 4 is an enlarged sectional view of the upper and inner mold. Fig. 5 is a view of the mechanism for lowering the movable portion of the bottom of the lower mold, the lower mold being shown in section. Fig. 6 is a view of the guide-plate for the movable central portion of the plunger.

Like numerals indicate like parts in each of the figures.

The numeral 2 designates a suitable base or support upon which is erected the frame comprising the standards 3. Journaled within the standards 3 is the main shaft 4, which is driven by the pulley 5. On the shaft 4 is a suitable clutch 6. Mounted on the shaft 4 is the pinion 7, which meshes with the gear-wheel 8 on the shaft 9. A pinion 10 on the shaft 9 meshes with the gear-wheel 11 on the shaft 12. On the outer end of the shaft 12 is the crank-disk 13, having the cross-head 14, engaging the slideway 15 in the guide-block 16, moving in the guides 17. A plunger-rod 18 is connected to the cross-head 14, the lower end of said cross-head being connected to the yoke 19 of the plunger 20, said yoke being connected to said plunger by means of

the bolts 21, passing through lugs 22 on said yoke.

Guide-rods 23 are mounted on the base 2, said guide-rods acting as guides for the plunger 20 and the mold 24. The yoke 19 has the guides 25, which engage the guide-rods 23, while the mold 24 has the guides 26, which also engage said rods. The plunger 20 and mold 24 are adapted to approach each other, moving in opposite directions, so that the one enters within the other, and to provide for this movement the levers 27 are fulcrumed at 28 to the standards 29, the opposite ends of said levers having the slots 30, which engage the pins 31 on the guides 25. Links 32 connect the levers 27 through the levers 33, fulcrumed at 34 upon the brackets 35, secured to the standards 3. The outer ends of the levers 33 have the slots 36, which engage pins 37 on the guides 26 of the mold 24. By this construction as the plunger-rod is raised and lowered the plunger and mold 24 approach each other simultaneously until the plunger passes within the mold, as indicated in Fig. 2.

The plunger 20, as clearly illustrated in Fig. 4, comprises the outer shell 38 and the inner shell 39. Secured to the inner shell 39 is the false bottom 40, which is adapted to move with the inner shell 39 independently of the outer shell 38. Within the inner shell 39 is the supplemental plunger 41. A rod 42 engages a recess 43 in the supplemental plunger 41, said rod having the pin 44 within the enlarged portion 45 of the recess 43. A plate 46, secured to the supplemental plunger by the screws 47, prevents the withdrawal of the rod 42 from the supplemental plunger 41. A spring 48 encircles the rod 42 and is interposed between the plate 46 and plate 49, secured to the upper end of the inner shell 39 of the plunger. This plate, as indicated in Fig. 6, has a slot 50 formed therein, said slot having the enlarged circular portion 51. A key 52 is driven through the rod 42, said key being adapted to rest normally upon the plate 49, but being adapted when turned to enter the slot 50, all as

fully hereinafter set forth. Secured to the upper end of the rod 42 is the arm 53, said arm being secured to said rod 42 by the nuts 54. A spring 55 is connected with the one end of the arm 53, the other end of said spring being secured at 56 to the guide-lever 27. This arm 53 is arranged at an angle with reference to the yoke 19 of the plunger and at the same angle as the key 52 in the rod 42.

Rods 57 connect the false bottom 40 to the inner shell 39 of the plunger, said rods also acting to hold the plate 49 in position, and extending up are connected to the plate 58, which encircles the plunger-rod 18 and being adapted to move up and down on said plunger-rod. Lugs 59 on the plate 58 have the pin 60, adapted to engage the slot 61 in the lever 62. This lever 62 is fulcrumed at 63 upon the arm 64, secured to the yoke 19, so that said lever will be carried down by the plunger. The outer end of the lever 62 has the weight 63 secured thereto. Bolted to the guides 17 is the bar 62^a, with the shoulder 62^b, with which the lever 62 is adapted to engage. The lever 62 has sufficient lateral play to be readily released from said shoulder, so as to assume the position indicated in dotted lines, Fig. 1. The rods 57 are also connected to the cross-arm 66, from which depend the rods 67, which are connected to the stripper 68, which encircles the plunger 20 and which is adapted to strip the saggars therefrom, all as fully hereinafter set forth. The rods 67 have the pins 69, and between said pins and the cross-arm 66 are the springs 70.

Depending from the plunger 20 is the tripper-arm 71, with the tripper-finger 72 at the lower end thereof controlled by the spring 73. Pivoted at 75 to the mold 24 is the arm 74, said arm having the tripper-finger 76 in the path of the tripper-finger 72 of the arm 71. A spring 77 connects the tripper-arm 76 with the arm 74. By the tripper-finger 72 coming in contact with the tripper-finger 76 the upper end of the arm 74 is thrown over into position to engage the arm 53 and to shift said arm slightly for the purpose fully hereinafter set forth.

The mold 24 has the movable bottom 78, which rests upon the standard 79. Connected to the bottom 78 is the yoke 81, which has the collar 82, adapted to slide up and down on the standard 79. On the collar 82 is the projection 82^a in the path of the mold 24 on its descent. A lever 83 is connected to the collar 82, said lever being fulcrumed at 84 and having the weight 85 at the outer end thereof. This weight acts to normally lift or raise the bottom 78 from the standard 79. In addition to the means for raising the bottom 78 by means of the weight 85 I employ the following auxiliary means: An arm

86 is secured to the yoke 81, said arm having the lip 87, which is adapted to engage the recess 88 in the lower end of the swinging arm 89, which is hung at 90 from the plunger. The lugs 91 and 92, which form the recess 88, are beveled, so that the mold will act to release the arm 89 from the lip 87 of the arm 86 when said mold descends, as fully hereinafter set forth. By thus locking the movable bottom 78 to the yoke 81 it is apparent that as the plunger ascends the bottom 78 will ascend with it until the mold 24 has descended sufficiently to trip the arm 89 and release said bottom from the yoke 81.

In the operation of forming saggars with the above apparatus the clay from which the saggars are formed is placed upon the bottom of the mold 24, whereupon the clutch 6 is thrown to drive the pinion 7 and 8, which through the gearing illustrated acts to lower the plunger-rod 18, carrying with it the plunger 20. The operator before the descent of the plunger releases the lever 62 from the shoulder 62^b on the bar 62^a, said lever assuming the position indicated by dotted lines, Fig. 1. Owing to the lever 27 and connecting parts, the mold 24 will be lifted, moving at the same rate of speed as the plunger 20. As the plunger enters the mold 24 the tripper-finger 72 engages the tripper-finger 76, and the arm 74 is thrown over into the path of the arm 53. This will tend to force the arm 53 around, carrying with it the rod 42 and the key 52. The key 52 will be brought around so as to coincide with the slot 50, whereupon the spring 48 will act to draw said key down through said opening, forcing the supplemental plunger 41 into the position indicated in dotted lines, Fig. 4. This supplemental plunger advancing ahead of the main plunger will act to distribute the body of clay within the mold so that when the main body of the plunger comes into contact with said clay the clay will be forced up and around the space between the plunger and the mold, so as to form the saggars of a substantially uniform thickness. As the plunger continues to descend the supplemental plunger 41 is forced up as the pressure increases, and the key 52 is forced up through the slot 50. Just as soon as the key passes beyond the upper face of the plate 49 the spring 55 will act to draw the arm 53 back to its normal position, carrying with it the key 52, which thereupon rests upon the upper face of the plate 49 and locks said supplemental plunger 41 in its former position. When the saggars have been formed in this manner, the plunger is withdrawn and the mold 24 descends. As the plunger ascends and the mold descends the weight 85 on the lever 83 will act to cause the movable bottom 78 to rise, or where the locking-arm 89 is employed said movable bottom will rise with the ascent of

the plunger. The said bottom 78 will continue to rise, the sleeve 82 sliding up the standard 79 until the mold 24 strikes the pin 82^a in the sleeve 82, whereupon the further descent of the mold will act to lower the bottom 78, or where the locking-arm 89 is employed said mold 24 in its descent will strike the beveled lug 92 of the locking-arm 89 and throw said arm out so as to release the movable bottom 78, when it will descend to its normal position, resting upon the standard 79. Where the weighted lever is employed, however, it will not be necessary to use this locking-arm 89, which may be swung out of the way, so as not to operate except in case of the failure of the weighted lever to do its work. The movable bottom 78 will be carried up until the saggar is free from the walls of the mold 24, whereupon said saggar may be readily lifted from said bottom before the descent of said bottom takes place. At the same time that the plunger ascends the lever 62, which has been carried down with the plunger, will engage the shoulder 62^b on the stationary bar 62^a, as clearly indicated in full lines in Fig. 1, which acts to hold the stripper 68 and holds the false bottom 40 and supplemental plunger 41 down within the saggar, so as to strip the saggar from the rising plunger, as indicated in Fig. 1. The operator then releases lever 62, whereupon said lever 62 rises to the position indicated in dotted lines, Fig. 1, the false bottom 40 and supplemental plunger 41 being raised to their normal position, leaving the saggar in position to be removed.

By the above construction provision is made for releasing the supplemental plunger automatically, so that it advances ahead of the main plunger and acts to distribute the clay, while at the same time the downward pressure on said supplemental plunger is taken up by the spring, and when the clay has been properly distributed to form the bottom of the saggar of substantially even thickness the supplemental plunger will be locked in position, so as to be flush with the bottom of the plunger, and will accordingly act in connection with said false bottom to free the saggar from the plunger.

What I claim is—

1. In apparatus for forming saggars, or like hollow bowls, the combination with a suitable frame, of a mold, a plunger, a supplemental plunger moving simultaneously with said plunger, means for lowering said supplemental plunger beyond said plunger, and means for retaining said supplemental plunger in its elevated position.
2. In apparatus for forming saggars, or like hollow bowls, the combination with a suitable frame, of a mold, a plunger, a supplemental plunger, means for automatically lowering said supplemental plunger beyond

said plunger, and means for retaining said supplemental plunger in its elevated position.

3. In apparatus for forming saggars, or like hollow bowls, the combination with a suitable frame, of a mold, a plunger, a supplemental plunger, means for lowering said supplemental plunger beyond said plunger, and means for automatically locking said supplemental plunger in its elevated position.

4. In apparatus for forming saggars, or like hollow bowls, the combination with a suitable frame, of a mold, a plunger, a supplemental plunger, a spring adapted to force down said supplemental plunger, locking means for holding said supplemental plunger in place, and means for releasing said locking means.

5. In apparatus for forming saggars, and like hollow bowls, the combination with a suitable frame, of a mold, a plunger, a supplemental plunger, a spring adapted to force down said supplemental plunger, a rod connected to said supplemental plunger, a spring bearing down on said supplemental plunger, a locking-plate having an opening through which said rod passes, a projection on said rod adapted to pass through said opening at a certain position of said rod, and means for turning said rod.

6. In apparatus for forming saggars, and like hollow bowls, the combination with a suitable frame, of a mold, a plunger, a supplemental plunger, a spring adapted to force down said supplemental plunger, a rod connected to said supplemental plunger, a spring bearing down on said supplemental plunger, a locking-plate having an elongated opening therein through which said rod passes, a projection on said rod adapted to enter said opening, and means for turning said rod.

7. In apparatus for forming saggars, and like hollow bowls, the combination with a suitable frame, of a mold, a plunger, a supplemental plunger, a spring adapted to force down said supplemental plunger, a rod connected to said supplemental plunger, a spring bearing down on said supplemental plunger, a locking-plate having an elongated opening therein through which said rod passes, a projection on said rod adapted to enter said opening, an arm on said rod, and means for turning said arm.

8. In apparatus for forming saggars, and like hollow bowls, the combination with a suitable frame, of a mold, a plunger, a supplemental plunger adapted to be lowered below said plunger, locking mechanism for retaining said supplemental plunger in its elevated position, and means for releasing said supplemental plunger by the movement of said mold and plunger.

9. In apparatus for forming saggars, and like hollow bowls, the combination with a suitable frame, of a mold, a plunger, a sup-

plemental plunger adapted to be lowered below said plunger, locking mechanism for retaining said supplemental plunger in its elevated position, tripping mechanism carried by said mold and plunger, and connections between said tripping mechanism and said locking mechanism for releasing same.

10. In apparatus for forming saggars, and like hollow bowls, the combination with a suitable frame, of a mold, a plunger, a supplemental plunger, a spring adapted to force down said supplemental plunger, a rod connected to said supplemental plunger, a locking-plate having an elongated opening therein through which said rod passes, a projection on said rod adapted to normally rest on said plate, an arm on said rod, a pivotal arm on said mold, and means for throwing said swinging arm into contact with said arm on 20 said rod.

11. In apparatus for forming saggars and like hollow bowls, the combination with a suitable frame, of a mold, a plunger, a supplemental plunger, a spring adapted to force down said supplemental plunger, a rod connected to said supplemental plunger, a locking-plate having an elongated opening therein through which said rod passes, a projection on said rod adapted to normally rest on 25 said plate, an arm on said rod, a pivotal arm on said mold, and means for throwing said swinging arm into contact with said arm on 30 said rod.

35. 12. In apparatus for forming saggars, and like hollow bowls, the combination with a suitable frame, of a mold, a plunger, a supplemental plunger, a spring adapted to force down said supplemental plunger, a rod connected to said supplemental plunger, a locking-plate having an elongated opening therein through which said rod passes, a projection on said rod adapted to normally rest on 40 said plate, an arm on said rod, a tripper-arm on said plunger, a pivotal arm on said mold in the path of said tripper-arm and adapted to be thrown into contact with said arm on 45 said rod.

45. 13. In apparatus for forming saggars and like hollow bowls, the combination with a suitable frame, of a mold, a plunger, said mold and plunger moving in opposite directions, a movable bottom plate in said mold and a weighted lever connected to said bottom plate and adapted to elevate same.

50. 14. In apparatus for forming saggars and like hollow bowls, the combination with a suitable frame, of a mold, a plunger, said mold and plunger moving in opposite directions, a movable bottom plate in said mold, and means for raising said bottom plate as the

mold descends, and means for lowering said bottom plate by the descent of said mold. 65

15. In apparatus for forming saggars and like hollow bowls, the combination with a suitable frame, of a mold, a plunger, said mold and plunger moving in opposite directions, a movable bottom plate in said mold, 70 a weighted lever adapted to elevate said bottom plate and a projection carried by said movable bottom plate in the path of the descending mold.

16. In apparatus for forming saggars and like hollow bowls, the combination with a suitable frame, of a mold, a plunger, said mold and plunger moving in opposite directions, a movable bottom plate in said mold, 80 a standard upon which said bottom plate rests, a sleeve engaging said standard and connected to said bottom plate, and a weighted lever adapted to elevate said bottom plate and means for lowering said bottom plate by the descent of said mold. 85

17. In apparatus for forming saggars and like hollow bowls, the combination with a suitable frame, of a mold, a plunger, said mold and plunger moving in opposite directions, a movable bottom plate in said mold, 90 a swinging latch-bar on said plunger, a projection carried by said bottom plate adapted to be engaged by said latch-bar, and means for releasing said latch-bar by the descent of said mold. 95

18. In apparatus for forming saggars and like hollow bowls, the combination with a suitable frame, of a mold, a plunger, said mold and plunger moving in opposite directions, a movable bottom plate in said mold, 100 a swinging latch-bar on said plunger, beveled lugs on said latch-bar, a projection carried by said movable bottom plate adapted to be engaged by said lugs, said lugs being in the path of the descending mold. 105

19. In apparatus for forming saggars, and like hollow bowls, the combination with a suitable frame, of a mold, a plunger, stripping mechanism carried by said plunger, and means for holding said stripping mechanism 110 stationary as the plunger ascends.

20. In apparatus for forming saggars, and like hollow bowls, the combination with a suitable frame, of a mold, a plunger, stripping mechanism, a lever connected to said stripping mechanism and to said plunger, and a stop in the path of said lever. 115

21. In apparatus for forming saggars, and like hollow bowls, the combination with a suitable frame, of a mold, a plunger, stripping mechanism, a lever connected to said stripping mechanism and to said plunger, and a shoulder on said frame with which said lever is adapted to engage. 120

22. In apparatus for forming saggars, and like hollow bowls, the combination with a 125

suitable frame, of a mold, a plunger, a stationary bottom, a movable bottom portion, and means for lowering said movable portion by the movement of said mold.

5 23. In apparatus for forming saggars, and like hollow bowls, the combination with a suitable frame, of a mold, a plunger, a stationary bottom in said mold, a movable bot-

tom portion, and a projection on said movable bottom portion in the path of said mold. ¹⁰

In testimony whereof I, the said WILLIAM POLK, have hereunto set my hand.

WILLIAM POLK.
